BOWLING ALLEY

Henry E. Gremp and Edward C. Gremp,
Chicago, Ill.

Application November 8, 1940, Serial No. 364,874

22 Claims. (Cl. 273—51)

Our invention relates in general to runway construction and has more particular reference to bowling alleys.

An important object of the invention is to provide an inexpensive, yet durable runway construction particularly well suited for use in building bowling alleys.

Another important object is to provide an alley construction having simplified means for leveling the floor thereof; a further object being to mount the runway on spaced support beams arranged at intervals along the runway, and to provide for adjusting the beams in order to level the alley or alleys carried thereby; a still further object being to mount a plurality of alleyways in a set of beams common to all of the alleys.

Another important object is to provide a runway structure adapted to be erected in locations exposed to the weather, or otherwise exposed to excessive atmospheric moisture, without impairing the accuracy of the surface of the runway throughout a long service life; a further object being to provide an outdoor bowling alley which need not be enclosed or otherwise protected from the weather.

Another important object is to form a bowling alley embodying sheet metal sections forming gutters in the bowling alley structure; a further object being to utilize sheet metal sections for edge gutters as well as for ball return track means in a bowling alley structure.

Another important object is to provide a bowling alley structure having a ball return track having portions extending substantially beneath the level of the alley floor between the pit end of the bowling alley and the delivery end thereof; a further object being to enclose the top of the ball return track and thus conceal the balls from view during the returning travel thereof from the pit end of the alley to the delivery end thereof.

Another important object is to arrange the ball return track in a bowling alley beneath the edge gutters thereof, whereby to conserve space, as well as to enclose the ball return track and thereby prevent interference with the travel of balls along the return track.

Another important object is to provide a sheet metal gutter having fiber rails secured therein for the purpose of forming a trackway for balls; a further object being to provide novel clamping means for securing the rails in the sheet metal gutter.

Another important object resides in providing an improved combination of sheet metal and

monolithic material, such as cement, and a composition surfacing material for use in the construction of bowling alley floors; a further object being to provide means forming a foul line marking in a floor of the character mentioned.

Another important object is to provide an improved pit floor structure of weather resisting character for bowling alleys.

Still another important object resides in providing an improved arrangement for supporting alley floors and associated edge gutters and ball return trackways on laterally extending beams.

Another object resides in providing a novel arrangement of a ball return gutter for adjacent pairs of bowling alleys, whereby one ball return trackway may serve both alleys.

These and numerous other important objects, advantages, and inherent functions of the invention will become apparent as the same is more fully understood from the following description, which, taken in connection with the accompanying drawings, discloses alley structures embodying our present invention.

Referring to the drawings:

25. Figure 1 is a perspective view of a bowling alley embodying our present invention;

Figures 2, 3 and 4 are sectional views taken substantially along the lines 2—2, 3—3 and 4—4 in Fig. 1;

30. Figure 5 is a detail sectional view similar to Figure 4, but showing a modified alley structure embodying our present invention;

Figure 6 is a detail sectional view taken along the line 6—6 in Figure 1;

35. Figures 7, 8 and 9 are enlarged sectional views taken substantially along the lines 7—7, 8—8 and 9—9 in Figure 1;

Figure 10 is a modified pit end structure; and

Figure 11 is a sectional view taken substantially

40. along the line 11—11 in Figure 10.

To illustrate the invention, the drawings show a bowling alley structure 11 comprising means forming a pair of adjacently disposed alleys 13 forming a bowling alley set, each alley comprising 45 a runway or floor 15 having a pit construction 17 at one end and a delivery platform 19 at the other, said alleys being adjacent and each having edge gutters 21 at their opposite side edges, and the structure includes ball return track-

50. way means 23 along which balls may be returned from the pit end of the alleys to a ball rack 27 at the delivery end of the alleys, the rack 27 preferably, though not essentially, being arranged between the adjacent platforms 19 of the alley set.

The alley structure is preferably carried on piers 43 which may conveniently comprise wooden posts or blocks fastened in the ground or other base on which the alley structure is erected. The piers are arranged in spaced rows at the opposite sides of the alley structure, each area containing piers in vertical alignment laterally of the alley structure.

The runway or floor 15 of each alley is preferably carried on a supporting sub-structure comprising longitudinally extending members 29 disposed along the opposite sides of each alley 13. These members 29 are preferably iron channels formed in sections to facilitate transportation to the erecting site and are adapted to be assembled in abutting end-to-end relationship and secured together in any suitable or convenient fashion, as by bolting with fish plates, welding, or otherwise, to form rails.

The longitudinally extending support members 29 are secured at intervals throughout the length of the alley floor, as by bolting the same upon laterally extending beams 31 which may conveniently comprise I-beams, the opposite ends of which are secured, as by bolting, to plates 33. The plates 33 extend outwardly of the ends of the I-beams and carry each a threaded embossment 35 for the reception of a threaded adjusting stem 37 comprising a threaded rod having a non-circular head 39 of preferably square sectional configuration at one end for the reception of a turning tool. The opposite end of the member 37 is formed to bear on a bearing plate 41 which is secured preferably on the upper end of a pier or post 43, Figs. 4 and 5.

It will be seen from the foregoing that each of the beams 31 is adjustably supported at its opposite ends on piers at the opposite sides of the alley structure, and it will be apparent that one or more alley floors may be supported on the same beam. In the illustrated embodiment, a pair of alley floors forming a set are supported on the same row of beams 31. It will be seen also that the plates 33 may support the abutting ends of beams 31 carrying adjacent alley structures, since the plate 33 has beam-engaging portions extending outwardly on opposite sides of the adjusting stem 37.

The support members 29 preferably comprise angle portions 47 and channel portions 49 and may comprise an integral unit with one flange of the angle portion forming a flange of the channel portion. Preferably, however, the portions 47 and 49 are formed separately and secured together by fastening means 45.

The floors 15 of the alleys are carried between the spaced support means 29, the opposite edges of each floor resting upon the joined flanges of the angle portion 47 and the channel portion 49. The floor 15 may, of course, be of any suitable or preferred construction, but in order that the alley may be weather resistant, the floor 15 is preferably formed of weather-proof material. To this end, the floor preferably comprises support means 51, which is shown in the illustrated embodiment as corrugated sheet metal means, the same being assembled on and between the supports 29 with the corrugations 53 extending laterally therebetween. The opposite edges of the corrugated sheet material 51 are preferably anchored on the spaced support members 29 by means of the fastening elements 45.

The corrugated sheet metal support means 51 carries a preferably monolithic sub-floor 55 which may conveniently comprise concrete, which, 75

if desired, may be suitably reinforced by means of steel or other reinforcing members extending therein. Ordinarily, however, the corrugated sheet material 51 will afford adequate reinforcement for the floor span between the support members 29. The concrete material 55 fills the space between the upstanding flanges of the angle portions 47 approximately to the level of the upper edges of said flanges, and a surfacing layer 57 of any suitable character is applied upon the concrete as a finishing layer. The layer 57 preferably comprises a weather-proof, resilient mastic material adapted to be finished to provide a relatively hard, long wearing, weather resistant playing surface, and to this end, granulated or powdered wood, together with a binder and suitable non-soluble adhesives, may be employed to advantage. After the surfacing layer has been applied, it may be finished smooth by the use of sanding machines and coated with shellac.

The support means 29 at intervals carry gutter support brackets 61, which preferably comprise sheet metal pieces formed with lateral flanges 63 for attachment, as by bolting, to the members 29 at one end of the bracket. The other end of the bracket is formed with flange means 64 for connecting the same on support means spaced from the members 29, and such support means may be the member 29 of an adjacent alley, or may be a separate bracket support member. The members 61 are each formed with a reinforcing flange 65 along the lower edge thereof and are formed with gutter supporting flanges 67 in the upper edge of the bracket.

As shown in Figure 4 of the drawings, one end of the brackets 61 is secured, as by bolting, to the member 29 and extends outwardly thereof at the side of the alley, the opposite end of the bracket being fastened, as by bolting, to angle means 69 extending longitudinally at the side of the alley and secured, as by bolting, on the beams 31. The edge gutters 21 have edges bent to form flanges 71 which are assembled in position overlying the inner faces of the upstanding flanges of the angle members 47, the flanges 71 being secured in place at intervals by fastening members 73 so that the gutters are firmly connected along one edge at the edge of the alley floor structure, said connection, of course, being made before the monolithic material 55 is placed. It will be noted that the monolithic layer 55 completely covers the gutter flange 71 and that the edges of the finishing layer 57 overlie the inner edge of the gutter, and in order to protect the edges of the layer 57 where the same meet the gutter, a preferably sheet metal retaining strip 75 is provided. The medial portions of the gutter 21 rest upon the gutter supporting flanges 67 of the bracket 61, and a rubber plate 77 is preferably interposed between the bottom of the gutters and the supporting flanges 67 for silencing purposes.

The outer edges of the gutters 21 are provided with upstanding flanges 79 for attachment, as by riveting or bolting, on the extensions of the bracket flange 64. As shown in Figure 4 of the drawings, the ball return trackway 23 is arranged in position extending between adjacent alleys 13 of an alley set supported upon a row of beams 31, the return trackway being carried by the beams between the adjacent alleys. The return trackway comprises a preferably sheet metal trough 81 in the bottom of which spaced-apart rails 83 are mounted. These rails preferably comprise strips of fibre material, the upper edges of which are rounded to receive the ball and

support the same for further rolling movement therealong. The rails 83 may be secured in place in any suitable or preferred fashion and, as shown, may be clampingly mounted in channels 85 fastened in the bottom of the troughs 81 as by welding, riveting or bolting.

It will be seen that the return trackway will support the ball between and below the level of the edge gutters 21 of adjacent alleys, and the trackway is preferably enclosed between said edge gutters in order to conceal the ball during its traveling movement along the trackway and prevent interference therewith. The trackway is enclosed by a preferably sheet metal cover 87 comprising sheet metal moldings 89 having flanges secured to the gutter flange 79. The cover means 87 also may include removable panel means 91, Fig. 6, frictionally held between angle pieces 93 welded or otherwise secured to the moldings 89, the panels 91 being formed with finger-receiving openings 95 by means of which the same may be removed in order to give access to the enclosed trackway.

If the structure of any particular alley requires the arrangement of the enclosed trackway 23 at the edge of an alley structure rather than between adjacent alleyways, one side of the trackway-enclosing housing may be finished as shown in dotted lines in Figure 4. In Figure 5 of the drawings is shown a modified arrangement of return trackways in which the same are supported at the side of an alley structure on the gutter supporting brackets 61 which, in addition to the gutter flanges 67, are provided with extensions 97 flanged as at 99 to provide support for the return trackway 23. As shown in Figure 5, the rails 83 of the trackway are mounted in a preferably sheet metal rail support 101 which is secured, as by means of the bolts 103, to the bracket flanges 99. The rail support 101 may be flanged as at 105 for connection with a molding 107 which may be secured to the flange 79 of the adjacent alley edge gutter.

The alley remote side of the trackway 23 may be finished in any desired fashion to enclose the side of the alley structure, or the alley structure may be integrated with the structure of an adjacent alley, as shown, by joining each of the brackets 61 with the corresponding bracket of the adjacent structure by bolting or otherwise securing angle members 109 therebetween. In such an event, the alley remote sides of the track members 101 may be formed with flanges 111 extending to and secured upon the support members 109, which may carry a walking deck 113 thereon between the return trackways of adjacent alley sets. This walking deck may be of any suitable or preferred construction and is shown as comprising corrugated sheet metal 115 supported on the angle members 109 between the spaced flanges of adjacent trackways and monolithic material 117 formed on the corrugated sheet material 115 to provide a walking deck.

As shown more particularly at 119, adjacent alley sets may be interconnected by means of integral gutter support brackets 161, which may be formed either by stamping as a single piece or by suitably fastening together a pair of brackets 61. In either case, the space between the adjacent gutters 21 of adjacent alleys may be finished by means of a cover molding 121 having spaced flanges for attachment, as by means of screws 123, on the flanges 79 of the adjacent gutters, which flanges also may have bent edges clamped together within the cover 121 by means

5 of the bolts 125. In such an event, the clamped edges of the flanges are cut away at intervals to provide openings vertically above the adjusting members 37, so that a turning instrument may be applied thereto upon removal of a section of the cover molding 121.

In like fashion, where the adjusting screws 37 are disposed vertically beneath the trackways 23, as shown more particularly in Figure 5 of the drawings, openings are formed at intervals in the member 101 through which access to the operable ends of the adjusting members 37 may be had.

At the pit end of the alley, the terminal I-beam 31 supporting the end of the alley floor is provided with bracket means 127, preferably an angle member, on which is hung one end of a pit floor structure comprising spaced channel members 128, the other end of which is carried on an I-beam 131 supported at its opposite ends on a pair of spaced piers 143 by screw-threaded adjusting means similar to the adjusting means used in mounting the beams 31 on the piers 43. The pit floor structure 128 preferably comprises a metallic grille 132 supported at its opposite side edges on the spaced channel members 128, which are fastened at one end on the bracket 127 and at the other on the I-beam 131, Figs. 3 and 7. A preferably perforated rubber mat 134 is applied upon the grille 132 to protect balls from damage in dropping onto the pit floor. The spaced channel members 128 may also be used to support a removable, preferably sheet metal pan or tray 136 beneath the grille 132, said tray being removable from the rear of the pit and serving as a dust collector to catch such debris as may drop through the grille.

The pit end of the alley structure may be of any suitable style and construction, but preferably is formed of pre-fabricated metal elements, including corner posts 133 which may be anchored in the floor, foundation, or ground on which the alley is erected, as by driving the same into position. The posts 133 are interconnected 45 by means of a rail 135 secured in place, as by bolting, welding or other suitable fastening means. The rail 135 carries a back-stop cushion tiltably hung thereon for swinging movement between the posts 133. On each side of each alley, 50 wings are provided, said wings comprising metal plates attached on the opposite sides of the posts 133 and additional posts in alignment therewith along the opposite sides of the alley structure at the pit end thereof and between the pits of adjacent alleys. Sheets of fibrous material may be applied, as by means of rivets or other suitable fasteners, upon the surfaces of the metal plates forming the pit wings in order to receive the impact of balls and suppress the noise of impact.

60 The return trackway 23 includes elevated portions 145 at the alley end of the structure, which elevated portions are supported on one of the wings of the pit structure. In the event that the return trackway is arranged between adjacent alleys of a set, the center wall of the alley structure will, of course, be utilized to support the elevated portions of the return trackway, which will terminate, as at 139, at the rearward extremity of the central partition. In the event that the return trackway is arranged in position extending along one side of the alley structure, the elevated portions of the trackway may be extended across the back of the pit, in which 70 event it will be supported upon the rail 135 in

order that both pits of an alley set may be served by the single return trackway.

At the delivery end of the alley structure, the platforms 19 may comprise extensions of the alley floors 15. To this end, the support members 29, at the end of the alley floors, carry a channel member 141 secured thereto in any suitable fashion, as by means of the angle members 147. The member 141 supports an angle member 149 at the delivery end of the alley floors, and this angle member carries fibre strip means 151 comprising a foul line marker defining the delivery end of the alleys, the alley floor material 57 terminating at said marking strip 151, the upper edge of which is flush with the surface of the floor layer 57. The channel member 141 supports the ends of the channels 129, comprising continuations of the members 29, the remote portions of said members 129 being carried on beams similar to the beams 31 and similarly mounted on floor supporting piers at the delivery end of the alley structure. The channels 129 are suitably secured together in spaced relationship, as by means of an angle member 153, and carry corrugated sheet metal floor supporting means thereon, the delivery platform comprising monolithic material such as cement 155 applied on the sheet metal means and covered by a surfacing layer 157.

At the delivery end of the alley structure, the return trackway 23 connects with the ball rack 27, which is provided with a ball check 159 of any suitable, preferably sheet metal and fibre, construction for reducing the speed of return balls as the same enter the ball rack 27. The end of the ball rack 27 is supported on a newel post, which is preferably constructed of weather resisting sheet metal.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the forms herein disclosed being preferred embodiments for the purpose of illustrating the invention.

The invention is hereby claimed as follows:

1. A bowling alley comprising metallic members arranged in end-to-end relationship to form spaced-apart sectional floor edge retaining and supporting means extending longitudinally of the alley and affording facing ledges, plate means supported, at the opposite edges of the plate means, on said facing ledges, monolithic means on said plate means in position extending between said spaced-apart edge retaining and supporting means to form an alley floor, laterally extending beams carrying said floor edge retaining and supporting means at intervals, and means for individually adjusting the elevation and angularity of said beams for floor leveling purposes.

2. A bowling alley comprising metallic members arranged in end-to-end relationship to form spaced-apart sectional floor edge retaining and supporting means extending longitudinally of the alley and affording facing ledges, plate means supported, at the opposite edges of the plate means, on said facing ledges, monolithic means on said plate means in position extending between said spaced-apart edge retaining and supporting means to form an alley floor, longitudinally extending sheet metal trough means forming a gutter having an edge secured to the

floor edge retaining and supporting means at an edge of said floor, laterally extending beams carrying said gutter and said floor edge retaining and supporting means at intervals, and means for individually adjusting the elevation and angularity of said beams for floor and gutter leveling purposes.

3. A bowling alley comprising monolithic means forming an alley floor, sheet metal trough means forming a gutter having an edge embedded in said monolithic means along a longitudinal edge of said floor, laterally extending beams supporting said floor at intervals, means supporting said gutter on said beams, and means for individually adjusting the elevation and angularity of said beams for leveling said floor and said gutter.

4. A bowling alley comprising monolithic means forming an alley floor, channelled members in end-to-end relationship forming longitudinally extending floor supporting rail means defining the opposed edges of said floor, longitudinally extending sheet metal means forming a gutter having an edge secured to the rail means along a longitudinal edge of said floor, laterally extending beams carrying said longitudinally extending rail means at intervals, and bracket means supporting said gutter at intervals on said longitudinally extending rail means.

5. A bowling alley comprising monolithic means forming an alley floor, metallic section members arranged in end-to-end relationship to form longitudinally extending spaced-apart floor carrying means at the opposite side edges of the floor, sheet metal means forming a gutter having an edge embedded in said monolithic means along a longitudinal edge of said floor, laterally extending beams supporting said floor carrying means at intervals, means supporting said gutter on said floor carrying means, and means forming a return trackway for balls supported on said beams.

6. A bowling alley comprising means forming an alley floor, sheet metal trough means forming a gutter having an edge secured along a longitudinal edge of said floor, means forming a ball return trackway adjacent the floor remote edge of said gutter, and sheet metal cover means having an edge connected to said gutter along the floor remote edge thereof and enclosing said return trackway.

7. A bowling alley comprising means forming a pair of adjacent alley floors in spaced relationship, a series of laterally extending beams supporting said floors at intervals, each beam supporting both floors, and means for individually adjusting the elevation and angularity of said beams for floor leveling purposes.

8. A bowling alley comprising means forming a pair of adjacently extending alley floors, each floor being carried on longitudinally extending floor edge supporting members, a series of spaced-apart, laterally extending beams carrying said floor supporting members at intervals, each beam carrying the supporting members of adjacent alley floors, and means for individually adjusting the elevation and angularity of said beams for floor leveling purposes.

9. A bowling alley comprising means forming a pair of adjacent alley floors, a series of spaced-apart, laterally extending beams supporting said floors at intervals, each beam commonly carrying both of said floors, a ball return trackway supported on said beams between a spaced pair of said floors, and means for individually ad-

justing the angularity of said beams for floor leveling purposes.

10. A bowling alley comprising means forming a pair of adjacent alley floors, a series of spaced-apart, laterally extending beams supporting said floors at intervals, each beam commonly carrying both of said floors, a ball return trackway supported on said beams between a spaced pair of said floors, said return trackway being supported at an elevation substantially below the level of said floors, and means for individually adjusting the angularity of said beams for floor leveling purposes.

11. A bowling alley comprising means forming a pair of adjacent alley floors, a series of spaced-apart, laterally extending beams supporting said floors at intervals, each beam commonly carrying both of said floors, a ball return trackway supported on said beams between a spaced pair of said floors, means forming edge gutters at the adjacent edges of said alley floors, said gutters being located between the return trackway and the adjacent edges of said floors, and spaced sheet metal plates forming brackets supporting said gutters on said beams.

12. A bowling alley comprising means forming a pair of adjacent alley floors, a series of spaced-apart, laterally extending beams supporting said floors at intervals, each beam commonly carrying both of said floors, a ball return trackway supported on said beams between a spaced pair of said floors, sheet metal trough means forming edge gutters at and having edges secured to the adjacent edges of said alley floors, said gutters being located between the return trackway and the adjacent edges of said floors, and sheet metal means forming a cover carried by and secured to and extending between the facing edges of said gutters in position enclosing said trackway.

13. A bowling alley comprising metallic members arranged in end-to-end relationship to form spaced-apart sectional floor edge retaining and supporting means extending longitudinally of the alley and affording facing ledges, plate means supported, at the opposite edges of the plate means, on said facing ledges, monolithic means on said plate means in position extending between said spaced-apart edge retaining and supporting means to form an alley floor, laterally extending beams supporting said floor at intervals, a threaded sleeve at an end of each beam, and means for individually adjusting the elevation of each beam for leveling the floor, comprising a threaded stem in the sleeve thereof in combination with a bearing plate in position to receive the thrust of said stem.

14. A bowling alley comprising means forming an alley floor, elongated sheet metal means forming a ball return way extending adjacent an edge of said alley floor, a sheet metal trough member forming an edge gutter extending between said floor and said return way and having one edge secured to and along an edge of the floor and another edge secured to and along said return way, spaced-apart transverse beams supporting said alley floor at intervals, and spaced sheet metal plates forming common brackets supporting said gutter and said return way on said beams.

15. A bowling alley comprising means forming a monolithic floor structure, laterally extending beams supporting said floor structure at each end and intermediate the ends of the floor structure, metallic grille means forming a pit floor

at one end of said floor structure, longitudinally extending channels supporting the lateral edges of said grille, means supporting said channels on a floor supporting beam at one end of said floor structure, and adjustable means supporting remote portions of said channel members.

16. A bowling alley comprising means forming a monolithic floor structure, laterally extending beams supporting said floor structure at each end and intermediate the ends of the floor structure, metallic grille means forming a pit floor at one end of said floor structure, longitudinally extending channels supporting the lateral edges of said grille, means supporting said channels on a floor supporting beam at one end of said floor structure, and adjustable means supporting remote portions of said channel members, said channel members providing facing flanges for supporting a dust pan beneath said grille.

17. A bowling alley comprising means forming an alley floor having sheet metal trough means forming edge gutters along the lateral edges thereof, transverse beams supporting said floor and gutters at spaced intervals, means forming a ball delivery station at one end of said alley floor, means forming a pit at the opposite end of said alley floor, and sheet metal means forming a ball return tunnel containing track means therein extending between said pit and said delivery station adjacent and outwardly of one of said edge gutters, said return track means between said pit and delivery stations being depressed below the level of said alley floor and having portions elevated above the level of the alley floor at said pit and at said delivery station, said sheet metal means forming said tunnel being secured to and along the floor remote edge of the adjacent edge gutter.

18. A bowling alley comprising means forming a pair of adjacently extending alley floors, sheet metal trough means forming a gutter bordering each of the adjacent edges of said floors, each gutter having an edge secured along a longitudinal edge of the floor which it borders, elongated sheet metal means having opposed edges secured to the floor remote edges of said gutters to interconnect the same and close the space therebetween, a series of laterally extending beams supporting each of said floors at intervals, the beams carrying one floor having ends in spaced alignment with the abutting ends of corresponding beams supporting the other floor, and means for adjusting the elevation of the abutting ends of a pair of said beams, comprising a turnable member having an operable portion accessible through the space between the floor remote edges of said gutters.

19. A bowling alley comprising means forming an alley floor, longitudinally extending floor supporting rail means supporting an edge of said floor, an elongated sheet metal trough member forming a ball return track extending adjacent an edge of said alley floor, a sheet metal trough member forming an edge gutter extending between said floor and said track and having one edge secured to and along an edge of the floor and another edge secured to and along the edge of said track-forming trough member, spaced-apart plates forming brackets secured on said rail means and affording common support for said edge gutter and said return track, longitudinally extending channel means spaced from said rail means and supporting said brackets, and transverse beams supporting said rail means and said

channel means at intervals throughout the length of the alley floor.

20. A bowling alley comprising means forming a pair of adjacent alley floors in spaced relationship, channelled members in end-to-end relationship forming longitudinally extending floor supporting rail means defining the opposed edges of said floor, longitudinally extending sheet metal means forming gutters extending at and having edges secured along the adjacent edges of adjacent floors, gutter supporting brackets connected at intervals on said longitudinally extending floor supporting members and extending beneath said gutters to support the same, and means forming a walking aisle supported by said brackets and extending longitudinally of said bowling alley between said gutters.

21. A bowling alley comprising means forming a pair of adjacent alley floors in spaced relationship, channelled members in end-to-end relationship forming longitudinally extending floor supporting rail means defining the opposed edges of said floor, longitudinally extending sheet metal means forming gutters extending at and having edges secured along the adjacent edges of adjacent floors, gutter supporting brackets connected at intervals on said longitudinally extending floor supporting members and extending beneath said gutters to support the same, means forming a walking aisle supported by said brackets and extending longitudinally of said bowling alley between said gutters, and sheet metal closure means carried on said brackets and enclosing the space between the facing edges of said gutters and the opposed edges of said walking aisle.

ets and extending longitudinally of said bowling alley between said gutters, and sheet metal closure means carried on said brackets and enclosing the space between the facing edges of said gutters and the opposed edges of said walking aisle.

22. A bowling alley comprising means forming a pair of adjacent alley floors in spaced relationship, channelled members in end-to-end relationship forming longitudinally extending floor supporting rail means defining the opposed edges of said floor, longitudinally extending sheet metal means forming gutters extending at and having edges secured along the adjacent edges of adjacent floors, gutter supporting brackets connected at intervals on said longitudinally extending floor supporting members and extending beneath said gutters to support the same, means forming a walking aisle supported by said brackets and extending longitudinally of said bowling alley between said gutters, and sheet metal closure means carried on said brackets and enclosing the space between the facing edges of said gutters and the opposed edges of said walking aisle, said closure means being formed to provide a ball return trackway between one of said gutters and said walking aisle.
